US0D1078671S

(12) **United States Design Patent** (10) **Patent No.:** **US D1,078,671 S**
(45) **Date of Patent:** **** Jun. 10, 2025**

(54) **VEHICLE DISPLAY DEVICE**

(71) Applicant: **Shenzhen Yuzhongqi Technology Co., Ltd.**, Shenzhen (CN)

(72) Inventor: **Dayang Li**, Henan (CN)

(**) Term: **15 Years**

(21) Appl. No.: **29/958,603**

(22) Filed: **Aug. 20, 2024**

(51) **LOC (15) Cl.** **14-03**

(52) **U.S. Cl.**

USPC **D14/126**

(58) **Field of Classification Search**

(57) **CLAIM**

The ornamental design for a vehicle display device, as shown and described.

DESCRIPTION

FIG. 1 is a perspective view of a vehicle display device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown on the drawings depict portions of the vehicle display device that form no part of the claimed design.

1 Claim, 8 Drawing Sheets
